UNITED STATES PATENT OFFICE.

PINGREE H. MCKAY, OF BAY CITY, MICHIGAN.

SANITARY PAD.

Application filed September 16, 1923. Serial No. 135,978.

This invention relates to sanitary pads for refractors such as used by eye examiners and the like.

One object of the invention is to design a sanitary pad of simple and cheap construction, which can be readily placed on or removed from the machine, and which is not affected by the adjustment thereof.

A further object is to provide a sanitary pad of flexible absorbent material, and provide means for securing it in position.

With the above and other objects in view, the present invention consists in the production of a sanitary pad hereinafter fully described, illustrated in the accompanying drawing and particularly pointed out in the appended claims, it being understood that changes may be made in the form, size, and proportion without departure from the spirit of the invention.

In the drawings.

Fig. 1 is a front view showing my improved sanitary pad.

Fig. 2 is an edge view thereof.

Fig. 3 is a front view of a refractor showing the sanitary pad in place thereon, the lens discs of the refractor being shown in two different positions.

Fig. 4 is a top plan view thereof.

In the testing of eyes where the patient rests the face or portions thereof against any piece or part of the apparatus, it is essential from a sanitary standpoint, that these parts be covered with a suitable covering or pad which can be removed and renewed for each patient in order that the operation be entirely sanitary, and where the machine or part to which it is attached is adjustable, the pad must be designed to accommodate itself to said adjustments, and still cover the parts as above described, and I have therefore designed a pad which incorporates this feature, and which is easily replaced and attached.

Referring now to the drawing, the numeral 5 indicates the frame of a conventional refractor such as used by eye examiners, and to which the sanitary pad 6 is adapted to be applied, these refractors are operable by the eye examiner, and are provided with an up-standing pin 7 which is a part thereof, the

lenses and frame in which they are set being adjustable horizontally to suit the needs of the various patients, the refractor however forms no part of the present invention which is directed to the sanitary pad only.

The pad proper comprises a flat section of flexible absorbent material such as paper or the like, formed to shape as clearly shown in Figs. 1 and 2 of the drawing, and provided with an integral strip 8 having an opening 9 near the end thereof, this strip being bent at right angles to the main body, extending over the refractor, and is secured on the pin 7 thereof.

Spaced apart elongated slotted openings 10 and 10^a are provided in the face of the pad, so that as the distance between the centers of the lenses 11 is changed by adjustment, the pad will not obstruct or cover said lenses, the length of the slotted openings being the range of longitudinal adjustment of the refractor lenses.

From the foregoing description it will be obvious that I have perfected a simple, economical and convenient sanitary pad for refractors, which can be quickly removed and placed in position.

What I claim is:—

1. A sanitary absorbent pad formed of flexible material provided with spaced apart horizontally extending elongated openings, and a strip projecting from the upper edge thereof for securing the pad to a refractor frame.

2. A sanitary pad formed of flexible absorbent material and provided with centrally disposed spaced apart horizontally extending elongated openings, and a strip formed integral therewith and projecting from the upper edge thereof for securing the pad to a refractor frame.

3. The combination with the frame of a refractor, of a sanitary pad shaped to cover the lens frames thereof and provided with spaced apart horizontally extending elongated openings, and a laterally projecting strip on the upper edge thereof for securing the pad to the refractor frame.

In testimony whereof I affix my signature.

PINGREE H. MCKAY.
